UNITED STATES PATENT OFFICE.

BAGSTER ROADS SEABROOK, OF MISHAWAKA, INDIANA.

HORN FOR TALKING MACHINES.

Application filed June 17, 1918, Serial No. 240,475. Renewed June 20, 1924.

To all whom it may concern:

Be it known that I, BAGSTER ROADS SEABROOK, a subject of Great Britain, formerly resident of Canada and now a resident of 5 Mishawaka, in the county of St. Joseph and State of Indiana, have invented certain new and useful Improvements in Horns for Talking Machines, of which the following is the specification.

10 The invention relates to improvements in horns for talking machines, particularly amplifying horns and the general object of the invention is to provide an improved type of horn which will receive sound waves and deliver them in a full, clear, pure and 15 natural manner and without extraneous modifications.

A further object of the invention is to construct a horn with a specially treated 20 porous body.

A still further object of the invention is to construct a horn having a specially thickened neck arranged to effectively deliver unmodified sound waves to the body of 25 the horn and further to construct the body of the horn so that it presents an elliptical cross section at all points which gradually increases in cross sectional area in passing from the neck to the delivery end of the 30 horn.

With the above more important objects in view the invention consists substantially in a horn arranged and constructed as hereinafter more particularly described and 35 later pointed out in the appended claims, reference being had to the accompanying drawings in which:—

Fig. 1 represents a side view of the horn.

Fig. 2 represents a plan view of the same.

40 Fig. 3 represents an end view.

Fig. 4 represents a vertical sectional view through the horn, the section being taken in the plane denoted by the line X—X'.

Fig. 5 represents a sectional view transversely through the horn, the section being taken in the plane denoted by the line Z—Z'.

Fig. 6 represents an enlarged detailed sectional view through a portion of the neck of the horn.

50 Fig. 7^a represents a cross sectional view through the horn at Y—Y'.

Fig. 7 represents an enlarged detailed sectional view through a portion of the body of the horn.

55 Fig. 8 represents a vertical sectional view centrally through the neck.

In the drawings like characters of reference indicate corresponding parts in the several figures.

The horn indicated generally by the reference numeral 1 comprises what might be termed a flaring body part 2 and a neck 3 continuous with the body part and positioned more or less at right angles thereto: 60 4 represents the entry end of the horn and 5 the delivery end. The neck embodies an elbow like part 6 which elbow, for the purpose of the present description, is considered as that part of the neck appearing between the lines Z—Z' and X—X', and actually is the connecting part between the vertically disposed portion of the neck and the horizontally disposed inner end of the horn body. The vertically disposed part of the neck, that is to say that part extending 65 from the entrance end 4 to the line Z—Z', is circular in cross section and at the point where the elbow connects with the horn body the cross section is elliptical.

Between the one end of the elbow and the other, that is to say between the circular end and the elliptical end thereof, the elbow gradually merges from a circular shape into an elliptical shape and gradually increases in cross sectional area. On the 70 underside, as indicated at 7, the elbow is 75 slightly bellied or bulged.

The horn may be constructed in a particular manner being prepared from a shell 80 of paper-like material such as papier-mâché specially treated as shortly disclosed.

In making the horn I first shape the paper-like shell of the form herein before disclosed and of uniform thickness and then 85 treat the shell in the following way:—

It is first impregnated with a self-setting liquid solution which permeates the shell, filling the pores and which upon setting stiffens the shell. This part of the construction has been indicated by dots applied in 90 the enlarged sectional views shown in the drawings Figs. 6 and 7.

After the self-setting solution has set the whole horn may be given a coating of shellac, inside and out as indicated at 8 and as 95 soon as this has hardened I increase the thickness of the horn at the neck by applying a comparatively heavy coating of specially adapted non-shrinkable and very adhesive cement-like composition as indicated at 9. After the cement has hardened the 100 horn may then be covered with a linen-like 110

- fabric 10 that has been moistened by a suitable adhesive. This fabric is tightly drawn onto the horn with its edges overlapped. As the fabric dries it shrinks thus pulling it more tightly on the horn. If desired the horn may be given a further overall coating of shellac as instanced at 11 and after this is dry a final inside and outside coating of varnish may be applied as indicated at 12.
- 10 As soon as the varnish has become hard the horn is ready for use.
- A very important feature in the use of a porous paper-like body or support in connection with a very heavy coating of a non-
- 15 shrinkable cement-like composition applied at the neck of the horn is to insure its non-responsive and non-absorptiveness at the point where the sound waves are deflected toward the open end of the horn, thus by reason of the increased thickness at the neck being thoroughly incorporated with the paper-like support, results are secured which are superior to those secured with horns that do not have a non-shrinkable cement-like
- 20 composition incorporated therewith at and near the point where the principal waves are reflected. The composition away from this point is thinner toward the large end of the horn as shown in Fig. 8.
- 25 In horns which have a neck or elbow there is a tendency to remain mechanically weak where the bend occurs and in addition to become very absorptive of passing sound waves, a condition not found in horns which are formed without necks thus by reinforcing the neck with my cement-like composition the absorption of sound waves is prevented and the horn is made more rigid. While the description more especially relates to horns
- 30 for talking machines I do not limit myself to its use in connection with specific sources of sound productions as these may be mechanical, acoustical, electrical etc.

What I claim as my invention is:—

1. An amplifying horn body formed of a 45 porous paper-like material of approximately uniform thickness having an elbow at its small end, and a coating of cement-like composition placed on the body thicker at the elbow than at the large end of the horn. 50

2. A tapering amplifying horn having the body part terminating in a neck at the small end thereof, the whole being formed from paper-like material impregnated with a self-setting solution, and an extra thickness of 55 a non-shrinkable composition placed on the neck portion of the horn.

3. An amplifying horn having the body part thereof constructed from a cellular paper-like material impregnated with a self 60 setting solution, a cementitious composition in intimate contact with the body, an elbowed neck to said body said elbow being formed with an extra mass of the composition, and the neck elbow and body being 65 homogeneous continuations of each other.

4. An amplifying horn, a tubular body of paper-like material terminating in a reduced diameter at one end, a curved neck at this end, a coating of a self-hardening composition applied to said body, and an extra thick coating of the composition applied to the curved portion of said neck. 70

5. In amplifying horns, a conical body of paper-like material, a curved neck at the 75 small end, a coating of a self-hardening composition applied to said body thicker on the curved portion of the neck than at the large end of the horn, and a layer of fabric around the composition. 80

Signed at Winnipeg, this 29th day of May 1918.

BAGSTER ROADS SEABROOK.

In the presence of—

G. S. ROXBURGH,
K. B. WAKEFIELD.
